UNITED STATES PATENT OFFICE.

JAMES W. STEELE, OF CHICAGO, ILLINOIS, ASSIGNOR OF ONE-HALF TO
WILLIAM F. WHITE, OF SAME PLACE.

RAILWAY-SEMAPHORE.

SPECIFICATION forming part of Letters Patent No. 430,705, dated June 24, 1890.

Application filed November 22, 1889. Serial No. 331,208. (No model.)

To all whom it may concern:

Be it known that I, JAMES W. STEELE, of Chicago, in the county of Cook and State of Illinois, have invented a new, useful, and Improved Semaphore or Gate, of which the following is a full, clear, and exact description, reference being had to the accompanying drawings, forming parts of this specification, in which like letters of reference in the different figures designate corresponding parts.

The object of my invention is to provide a semaphore which may be so constructed and employed as to serve as a danger-signal for railway-trains or as a gate or barrier at railway-crossings, the same to be actuated either by the moving or carrying away of bridges, culverts, or portions of the railway-track by land-slides or washouts, or, if employed as a crossing-gate, by a tripper located upon the railway-track and moved by the wheels of a passing train, a single impulse, either by said tripper or otherwise, being requisite to actuate said semaphore, and that at the expenditure of but nominal force.

To these ends my invention consists in the combination of elements hereinafter more particularly described and claimed.

Figure 1 in the drawings represents a side elevation of an ordinary railway-culvert, showing my improved semaphore connected therewith and in its normal position. Fig. 2 is an enlarged front view, in detail, of said semaphore, the arm being broken off and a portion of the railway-track. Fig. 3 is a like view showing the semaphore-arm extended across the track and the working parts in abnormal positions. Fig. 4 is a plan view of said semaphore in an abnormal position. Fig. 5 is a rear end view of the same. Fig. 6 is a plan view in detail taken upon the line xx , Fig. 3. Fig. 7 is a plan view similar to that shown in Fig. 4 and embodying a modification of said invention. Fig. 8 is a plan view of a portion of a railway-track, showing a modification of my invention applied thereto and adapted to be used as a gate in connection with a tripper. Fig. 9 is a side view in detail of a portion of the railway-track, showing a tripper attached thereto; and Fig. 10 is a detail view showing a modification of said invention.

Referring to said drawings, a represents a railway-track, beside which is placed a rigid post b , to which is pivoted, by means of a shaft or trunnion b' , secured in a suitable bearing, a semaphore-arm c . Rigidly attached to said trunnion, and extending in an opposite direction from that of the semaphore-arm, is a short arm d , to which is by preference adjustably secured a counterpoise-weight d' . The main portion of the semaphore-arm is preferably made of a thin bar of metal, as shown at c' , so as to render it flexible, to which I prefer to attach a secondary bar c^2 , (better shown in Figs. 3 and 4,) which is parallel with the part c' and somewhat separated therefrom. The semaphore-arm is sufficiently long and so placed with relation to the track that when lowered, as in Fig. 3, a passing train is brought into contact with it, which causes it to bend, as indicated in dotted lines in Fig. 4, and to strike against the projecting parts of the locomotive and cars, and thus by its unusual noise give warning of danger. The post c^2 , when employed, adds to the noise produced.

The base of the arm c is made to abut slightly in an opposite direction from that in which the arm is extended, and I attach loosely to said abutting portion, upon that side of the plane of the axis upon which it is designed to have the arm c fall, as at e , a link e , the opposite end of which is pivotally connected to a lever f at e^2 . A secondary link g has one end pivotally connected to said lever f at g' , while the other is attached in like manner to the post b at g^2 . Both of the links e g are formed in cross-section, as shown in Fig. 6, where they are connected with the lever f , so as to form a sheath for said lever and receive the same in the manner indicated in said figure. The short arm of said lever passes into the space formed between the parallel portions of the link e , while the long arm is sheathed in like manner in the link g , the bend or back of said links forming a stop to limit the backward movement of said parts after the joints e^2 g' have passed the dead-center, as shown in Fig. 2, in which position they are normally held by means of a spring h , attached to lugs h' h^2 , respectively, upon said links.

- The links e g , with their joint-connection to the lever f , form a knee-joint which the spring h serves to hold in the position shown in Fig. 1 when the joints have passed the dead-center in moving back, while it tends to bend and throw them in an opposite direction, as shown in Fig. 3, as soon as they have passed said center in an opposite direction, and finally eases the fall of said semaphore. Thus the same spring serves to lock and unlock said joint, and in the act of unlocking to draw down the semaphore from a vertical to a horizontal position, while the resistance of the spring cushions its fall. To the lower end of the arm f is attached a wire j , which, after passing around a pulley j' , may be attached to a bridge k , as shown in Fig. 1, or to the track itself if it is in a dangerous position subject to land-slides or washouts.
- It will be observed that but a single impulse is necessary to actuate the lever f so as to unlock it from the position shown in Fig. 1, when the semaphore is drawn down, as shown in Fig. 3. As this impulse requires but a nominal force, it is obvious that said arm may be attached to a tripper located upon the track.

In Figs. 8 and 9 I have shown a tripper in the form of a bell-crank lever pivoted at k' to the rail, one arm k^2 being held normally above the level of the rail by means of a spring k^3 , Fig. 9, while the other k^4 is attached to the wire j . By making the arm c longer and placing it parallel with and at the side of the track, as shown in Fig. 8, it may serve as a gate for a railway-crossing, the foremost wheel of the passing train serving to actuate it.

In lieu of making the arm c flexible, as shown in Fig. 4, it may be jointed, as shown at c^3 , Fig. 7, a spring c^4 being employed to keep it normally straight, but permitting it to yield upon contact with a passing train.

Among the advantages possessed by my improved device are, first, that the arrangement of the trigger-joint serves to give rigidity and strength to the semaphore and to retain it in a normal position, while a single and very slight impulse applied to the lever f serves to actuate it; second, being thrown across the track, and therefore brought into direct contact with the moving train, insures the attention of the engineer, who might fail to notice a signal-light; third, the arrangement of the knee-joint permits the impulse to be sudden and positive without danger of break-

ing any of the parts; fourth, being thrown across the track in the manner described, it may be seen, as well as heard, by the engineer, and it is immaterial in many cases whether it be broken or not so long as it serves to give the required warning, and, moreover, it is applicable to isolated and lonely places, where there is danger of washouts or land-slides and it is impracticable to secure the constant presence of an attendant. When employed as a gate, it may be adjusted to a normal position by means of a handle d^2 upon the arm d , as shown in Fig. 8.

While I prefer to employ the lever f in connection with the toggle-joint, it is obvious that it may be dispensed with and the wire j attached directly to the joint, as clearly shown in Fig. 10, in which the spring is also differently adjusted.

Having thus described my invention, I claim—

1. In a railway semaphore or gate, the combination of an arm pivoted to a stationary support, a knee-joint mechanism, the members of which are connected one to said arm and one to said support, a spring connecting said members, whereby the joint may be operated when thrown out of the dead-center, a lever-connection, to which said members are pivotally attached, and means, as a wire or cable, for connecting said lever with a railway bridge or track, whereby the movement of either may actuate said semaphore, substantially as shown and described.

2. The combination, with a railway, railway-bridge, or other structure to be guarded, of a semaphore held in its normal position by means of a toggle-joint, and means—such as a wire or cable—for connecting said toggle-joint with said guarded structure, substantially as shown and described.

3. The combination, with a railway, railway-bridge, or other structure to be guarded, of a semaphore, a toggle-joint consisting of the members e , g , and f , spring h , and a rod or cable for connecting said part f with the structure to be guarded, substantially as shown and described.

In testimony whereof I have signed this specification, in the presence of two subscribing witnesses, this 19th day of October, 1889.

JAMES W. STEELE.
